UNITED STATES PATENT OFFICE.

HENRY HORAN, OF EAST ORANGE, NEW JERSEY, ASSIGNOR TO THE LOWELL MANUFACTURING COMPANY, OF MASSACHUSETTS.

DESIGN FOR CARPET.

SPECIFICATION forming part of Design No. 24,978, dated December 10, 1895.

Application filed November 8, 1895. Serial No. 568,364. Term of patent 3½ years.

To all whom it may concern:

Be it known that I, HENRY HORAN, a citizen of the United States, and a resident of East Orange, in the county of Essex and State 5 of New Jersey, have invented a new and original Design for a Carpet and Border, of which the following is a specification.

This invention comprises two parts, namely: the design A for a carpet, and the design B 10 for a border; and I do hereby declare that the drawing accompanying this specification conveys to any one a clear understanding of the same, and is sufficient to enable such person to use my invention.

15 The design A is characterized by clusters of flower forms surrounded by waving bands of lacework intertwined with leaf and flower forms.

The design B is characterized by a panel of waving bands of lacework intertwined with 20 leaf and flower forms and clusters of flower forms.

What I claim, and desire to secure by Letters Patent, is—

1. In a design for a carpet, the body A, substantially as shown.
2. In a design for a carpet, the border B, substantially as shown.
3. The design for a carpet, comprising the body A and the border B, substantially as 30 shown.

In testimony whereof I have signed my name to this specification in the presence of two subscribing witnesses.

HENRY HORAN.
